UNITED STATES PATENT OFFICE.

WINIFRED B. REININGER, OF BATTLE CREEK, MICHIGAN.

LAMP-STOVE.

1,298,789.

Specification of Letters Patent. Patented Apr. 1, 1919.

Application filed June 28, 1918. Serial No. 242,352.

To all whom it may concern:

Be it known that I, WINIFRED B. REININGER, a citizen of the United States, residing at Battle Creek, Michigan, have invented 5 certain new and useful Improvements in Lamp-Stoves, of which the following is a specification.

This invention relates to improvements in lamp stoves.

10 The main objects of this invention are:

First, to provide an improved lamp stove which may be placed upon a table or stand and an ordinary kerosene burning illuminating lamp utilized for heating the stove and 15 also for illuminating purposes and the table or stand simultaneously used as a dining table or table for other purposes.

Second, to provide a structure having these advantages which is very stable and 20 secure.

Third, to provide a structure of this class which may be readily knocked down for storage or transportation and when knocked down the parts may be very compactly arranged.

25 Fourth, to provide an improved structure of this type which is simple and economical to produce and easy to assemble or disassemble.

30 Further objects, and objects relating to details and economies of construction and operation will definitely appear from the detailed description to follow.

I accomplish the objects of my invention 35 by the devices and means described in the following specification. The invention is clearly defined and pointed out in the claims.

A structure which is a preferred embodiment of my invention is illustrated in the accompanying drawing forming a part of this 40 specification, in which:

Figure I is a front view of a structure embodying the features of my invention, a portion of the skirt of the oven being broken 45 away to show the arrangement of the deflector and supporting plate.

Fig. II is a plan view with the top plate removed.

Fig. III is a plan view of the top plate.

50 Fig. IV is a side view of one of the legs.

Fig. V is a side view of the deflector and supporting plate.

In the drawing similar reference numerals refer to similar parts throughout the 55 several views.

Referring to the drawing, I provide a

top frame comprising outer bars 1 formed of strips of metal secured together at their corners by bolts 2, and inner bars 3 disposed in a spaced relation to the outer bars secured 60 together by bolts 4 at their crossing points and to the outer bars by the rivets 5. The ends of the inner bars are turned upwardly to provide top engaging lugs 6. The top 7 is provided with side recesses 8 adapted to 65 receive the lugs 6 there being notches 9 at the ends of the recesses for the lugs. The top plate is provided with downturned flanges 10 between the lugs and with a central chimney opening 11. The top plate thus 70 formed is securely attached to the top frame and may be formed of comparatively light sheet metal, the turned down flanges adding to the appearance and to the rigidity thereof. 75

The legs 12 are formed of bars folded upon themselves to provide horizontal feet portions 13 and horizontal top portions 14. These legs are disposed radially and their top portions detachably secured to the top frame by the bolts 2 and 4 which secure the top frame pieces together as described, ordinary stove bolts being used for this purpose. 80

The legs are formed to provide vertical 85 upright portions 15 to which I secure the lamp center rings 16, the rings being disposed in a spaced relation and detachably secured by the bolts 17. The rings are adapted to receive the lamp 18 and serve as a 90 supporting and locating means therefor as well as a bracing and reinforcing means for the legs.

The oven 19 is conventionally shown and I provide a deflector and supporting plate 95 20 having feet 21 whereby it is supported in a spaced relation on the top plate above the chimney opening 11.

With this arrangement of the parts, I provide a structure which when assembled is 100 very strong and rigid and at the same time is of very light weight so that it may be conveniently handled or it may be knocked down for transportation or storage. Articles other than the oven may be arranged 105 on the supporting plate.

By arranging the parts as I have described, the structure may be placed upon a stand or table and the table used as a dining table or for other work, there being an open unobstructed space between the legs to accommodate dishes and the like, the lamp being 110

available for illumination and at the same time the heat thereof being utilized.

While I have illustrated and described my improvements as adapted for a kerosene lamp of well known type gas or other lamps or burners may be successfully used. I have through practical experience found my improved lamp stove to be highly efficient and practical and to result in a great saving of fuel and well adapted for light housekeeping or the preparation of luncheons and the like.

Having thus described my invention, what I claim as new and desire to secure by Letters Patent is:

1. In a lamp stove, the combination of a top frame comprising outer side bars secured together at their ends and inner bars disposed in a spaced relation and parallel to the side bars and secured thereto at their ends and to each other at their crossing points, the ends of said inner bars being turned upwardly providing top plate engaging lugs, a removable top plate having a central chimney opening therein resting on said top frame and recessed on its sides to receive said lugs, said top plate having downturned flanges between said lugs, legs formed of bars folded to provide horizontal feet portions and horizontal top portions, said legs being disposed radially with their top portions detachably secured to the top frame at the corners thereof and at the crossing points of said inner bars by the securing bolts for the bars, and a center ring detachably secured to said legs and constituting a lamp holder and a brace member for the legs.
2. In a lamp stove, the combination of a top frame comprising outer side bars secured together at their ends and inner bars disposed in a spaced relation and parallel to the side bars and secured thereto at their ends and to each other at their crossing points, the ends of said inner bars being turned upwardly providing top plate engaging lugs, a top plate having a central chimney opening therein resting on said top frame and recessed on its sides to receive said lugs, said top plate having downturned flanges between said lugs, legs formed of bars folded to provide horizontal feet portions and horizontal top portions, said legs being disposed radially with their top portions secured to the top frame at the corners thereof and at the crossing points of said inner bars, a center ring secured to said legs, and a deflector and supporting plate arranged on said top plate above said chimney opening thereof.
3. In a lamp stove, the combination of a top frame comprising outer side bars secured together at their ends and inner bars disposed in a spaced relation and parallel to the side bars and secured thereto at their ends and to each other at their crossing

points, a removable top plate having a central chimney opening therein resting on said top frame, legs formed of bars folded to provide horizontal feet portions and horizontal top portions, said legs being disposed radially with their top portions detachably secured to the top frame at the corners thereof and at the crossing points of said inner bars by the securing bolts for the bars, and a center ring detachably secured to said legs.

4. In a lamp stove, the combination of a top frame comprising outer side bars secured together at their ends and inner bars disposed in a spaced relation and parallel to the side bars and secured thereto at their ends and to each other at their crossing points, a top plate having a central chimney opening therein resting on said top frame, legs formed of bars folded to provide horizontal feet portions and horizontal top portions, said legs being disposed radially with their top portions secured to the top frame at the corners thereof and at the crossing points of said inner bars, and a center ring secured to said legs.

5. In a lamp stove, the combination of a top frame comprising outer side bars secured together at their ends and inner bars disposed in a spaced relation and parallel to the side bars and secured thereto at their ends and to each other at their crossing points, a top plate having a central chimney opening therein resting on said top frame, legs formed of bars folded to provide horizontal feet portions and horizontal top portions, said legs being disposed radially with their top portions secured to the top frame at the corners thereof and at the crossing points of said inner bars, a center ring secured to said legs, and a deflector and supporting plate arranged on said top plate above said chimney opening thereof.

6. In a lamp stove, the combination of a top frame comprising outer side bars secured together at their ends and inner bars disposed in a spaced relation and parallel to the side bars and secured thereto at their ends and to each other at their crossing points, the ends of said inner bars being turned upwardly providing top plate engaging lugs, a top plate having a central chimney opening therein arranged on said top frame between said lugs, and legs formed of bars folded to provide horizontal feet portions and horizontal top portions, said legs being disposed radially with their top portions detachably secured to the top frame at the corners thereof and at the crossing points of said inner bars.

7. In a lamp stove, the combination of a top frame comprising outer side bars secured together at their ends and inner bars disposed in a spaced relation and parallel to the side bars and secured thereto at their

ends and to each other at their crossing points, the ends of the inner bars being turned upwardly to provide top plate engaging lugs, a removable top plate having a central chimney opening therein arranged on said top frame between said lugs and supporting legs for said frame.

8. In a lamp, the combination of a top frame, a top plate arranged thereon, legs formed of bars folded to provide horizontal feet portions with upright portions at the inner ends thereof, and a center ring secured to the upright portions of said legs and adapted to receive a lamp.

9. In a lamp stove, the combination of a

top frame, a top plate therefor having a central opening, legs formed of bars folded to provide feet portions and top portions, said legs being disposed radially with their top portions secured to the top frame, and a center ring secured to said legs constituting a brace therefor and adapted to receive a lamp.

In witness whereof, I have hereunto set my hand and seal in the presence of two witnesses.
